[57] CLAIM

The ornamental design for a test pack for evaluating the effectiveness of an ethylene oxide sterilizing apparatus or other gas sterilizing apparatus, as shown and described.

DESCRIPTION

FIG. 1 is a rear perspective view of a test pack for evaluating the effectiveness of an ethylene oxide sterilizing apparatus or other gas sterilizing apparatus, showing my new design;

FIG. 2 is a rear elevational view thereof;

FIG. 3 is a front elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a rear elevational view of another embodiment of the test pack for evaluating the effectiveness of an ethylene oxide sterilizing apparatus or other gas sterilizing apparatus, showing my new design;

FIG. 9 is a rear perspective view thereof;

FIG. 10 is a front elevational view thereof;

FIG. 11 is a top plan view thereof;

FIG. 12 is a bottom plan view thereof;

FIG. 13 is a right side elevational view thereof; and

FIG. 14 is a left side elevational view thereof.
